ROBERT E. BROWN, OF OLEAN, NEW YORK

AX GUARD

Application filed October 17, 1929. Serial No. 400,373.

This invention relates to axes and more particularly to a guard by means of which the cutting edge of the ax head may be shielded and prevented from becoming dulled or accidentally cutting a person when the ax is not in use.

One object of the invention is to provide a guard adapted to be carried by the handle of an ax and so constructed and mounted that it may be swung from a folded position in which it is nested within a portion of the handle to an extended position in which a portion of the guard extends along the cutting edge of the ax head in shielding relation thereto.

Another object of the invention is to so form the guard that when folded it may be reduced to a compact mass and disposed within a pocket formed in the ax handle without it being necessary to form a pocket of such size that the handle will be weakened sufficiently to cause it to be liable to break.

Another object of the invention is to allow the guard to be very easily moved from a folded to an extended position and fit properly about the cutting edge of the ax head even if the cutting edge has been worn away by repeated sharpenings.

Another object of the invention is to permit a spring to be used in connection with the guard and thereby cause the guard to be retained in either a folded or extended position.

The invention is illustrated in the accompanying drawing, wherein

Figure 1 is a view showing the improved guard applied to an ax and in an extended position for use, the view being partially in elevation and partially in section,

Fig. 2 is a sectional view through the handle with the guard shown in elevation and in a retracted or folded position.

Fig. 3 is a transverse sectional view through the guard and handle taken on the line 3-3 of Fig. 2, and

Fig. 4 is a view looking at the outer edge face of the shank of the guard.

The ax to which the improved guard has been shown applied includes the usual head

1 formed with an eye to receive the handle 2. The handle may be formed of wood or any other desired material and along its front is provided with a longitudinally extending pocket 3, one end of which is reduced in depth to provide a seat 4. A leaf spring 5 extends longitudinally within the pocket 3 and has one end portion resting against the seat 4 where it is secured by a pin 6 extending transversely through the ax handle and preferably formed with heads 7 at its ends, as shown in Fig. 3, so that the pin will be prevented from slipping out of place.

The guard by means of which the cutting edge of the ax head is to be shielded consists of a shield 8 and a shank 9 preferably formed of metal, although other materials may be employed. The shank 9 is U-shaped in cross section to provide a longitudinally extending channel for receiving the shield 8 and at its outer end the shank is provided with an end wall 10 constituting an abutment to limit outward swinging movement of the shield on its pivot 13. A pin 11 carried by the handle extends through the pocket and inner end portion of the shank to pivotally mount the shank for swinging movement from the extended position shown in Fig. 1 to the folded position shown in Fig. 2 and at its inner end the shank may, if so desired, be provided with a short wall or tongue 12 which bears against the free end portion of the spring 5 and allows the shank to be swung about its pivot without scoring the spring and causing the spring to be quickly worn through. It should also be noted that this provides an inner end of the shank with a flat face against which the spring bears when the shank is extended and thereby prevents the shank from being liable to accidentally swing towards a folded position when extended for use. The shield 8 is also U-shaped in cross section to provide a longitudinally extending channel into which the cutting edge of the ax head fits when the guard is in extended position for use and this shield has one end portion pivotally mounted between side walls of the shank 9 by a pin 13 and at its other end may

100

be formed with an end wall 14 which serves to engage the outer edge face of the ax head and prevent the shield from sliding longitudinally of the cutting edge towards a folded position when the guard is extended for use.

When the ax is in use, the guard is folded, as shown in Fig. 2, with the shield fitting into the shank between the side walls thereof and the shield and shank are disposed longitudinally within the pocket 3. The free end portion of the shield rests against the pin 11 and projects slightly from the pocket. Therefore, when use of the ax is no longer necessary, the shield may be easily grasped at its free end and drawn outwardly. In so doing the shank is drawn outwardly with it and the shield and shank moved to the position shown in Fig. 1 with the shield disposed in straddling relation to the cutting edge of the ax head. The end wall 10 of the shank prevents the shield from moving outwardly about its pivot 13 beyond the position shown in Fig. 1 and the end wall 14 by engagement with the outer edge of the ax head prevents the shield from accidentally sliding longitudinally of the cutting edge towards a folded position. In view of the fact that the free end of the spring bears against the tongue or short wall 12 at the pivoted end of the shank when the guard is extended the pressure exerted by the spring will retain the shank in the position shown in Fig. 1 and the shield will be held in proper engagement with the ax head. It will thus be seen that the guard will serve very effectively to shield the cutting edge of the ax head and prevent danger of the cutting edge being nicked if the ax is dropped when not in use and also prevent danger of a person being accidentally cut. When the guard is folded, it fits snugly into the pocket and as it bears against the spring 5 it will be retained in the pocket and prevented from accidentally swinging outwardly. A spring 15 is provided in the shank to engage the shield and prevent the shield from accidentally moving outwardly when folded. Therefore, there will be no likelihood of the guard accidentally moving outwardly toward an extended position and getting in the way or becoming bent or broken when the ax is in use.

Having thus described the invention, I claim:

1. An ax comprising a head, a handle extending from said head and formed along its front with a longitudinally extending pocket, and a guard for the cutting edge of the ax head movable from a folded position within the pocket to an extended position and consisting of an inner strip, and an outer strip pivoted to the inner strip and adapted to cover the cutting edge of the ax head when extended.

2. An ax comprising a head, a handle extending from said head and formed along its front with a longitudinally extending pocket, a guard for the cutting edge of the ax head movable from a folded position within the pocket to an extended position and consisting of a shank of a length to extend longitudinally within the pocket when folded and being pivotally mounted at one end, and a shield pivoted to the free end of said shank and adapted to extend along the cutting edge of the ax head in shielding relation thereto when the guard is extended.

3. An ax comprising a head, a handle extending from said head and formed along its front with a longitudinally extending pocket, and a guard for the cutting edge of the ax head movable from a folded position within the pocket to an extended position and consisting of a shank of a length to extend longitudinally within the pocket when folded and being pivotally mounted at one end, a shield pivoted to the free end of said shank and adapted to extend along the cutting edge of the ax head in shielding relation thereto when the guard is extended, and a spring in said pocket engaging said shank to yieldably retain the guard in folded and extended positions.

4. An ax comprising a head, a handle extending from said head and formed along its front with a longitudinally extending pocket, and a guard for the cutting edge of the ax head movable from a folded position within the pocket to an extended position and consisting of a shank of a length to extend longitudinally within the pocket when folded and being pivotally mounted at one end, and a shield pivoted at one end to the free end of said shank, the shield being channeled and adapted to straddle the cutting edge of the ax head in shielding relation thereto when the guard is extended.

5. An ax comprising a head, a handle extending from said head and formed along its front with a longitudinally extending pocket, and a guard for the cutting edge of the ax head movable from a folded position within the pocket to an extended position and consisting of a shank of a length to extend longitudinally within the pocket when folded and being pivotally mounted at one end and having spaced side walls and an end wall at its free end, and a channeled shield pivoted at one end between the side walls of said shank adjacent the free end thereof and bearing against the end wall thereof when swung outwardly, said shield being adapted to straddle the cutting edge of the ax head in shielding relation thereto when the guard is extended.

6. An ax comprising a head, a handle extending from said head and formed along its front with a longitudinally extending pocket, and a guard for the cutting edge of

the ax head movable from a folded position within the pocket to an extended position and consisting of a shank of a length to extend longitudinally within the pocket when folded and being pivotally mounted at one end and having spaced side walls and an end wall at its free end, and a channelled shield pivoted at one end between the side walls of said shank adjacent the free end thereof and bearing against the end wall thereof when swung outwardly, said shield being adapted to straddle the cutting edge of the ax head in shielding relation thereto when the guard is extended and when folded being disposed between the side walls of the shank with its free end bearing against the pivot pin of the shank and projecting from the pocket whereby the shield may be grasped and together with the shank swung outwardly to an extended position.

20 In testimony whereof I affix my signature.
